US00D935316S

(12) **United States Design Patent** (10) **Patent No.:** **US D935,316 S**
(45) **Date of Patent:** **** Nov. 9, 2021**

(54) **PACKAGING WITH ACCESSORY**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Daniele De Iuliis**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Joe Sung-Ho Tan**, San Francisco, CA (US); **Clement Tissandier**, San Francisco, CA (US); **Eugene Antony Wang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/780,695**

(22) Filed: **Apr. 26, 2021**

Related U.S. Application Data

(63) Continuation of application No. 29/751,357, filed on Sep. 21, 2020, now Pat. No. Des. 917,303, which is (Continued)

(74) *Attorney, Agent, or Firm* — Sterne, Kessler, Goldstein & Fox P.L.L.C.

CLAIM

The ornamental design for packaging with accessory, as shown and described.

DESCRIPTION

FIG. 1 is a bottom front perspective view of packaging with accessory showing the claimed design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The broken lines in the figures show portions of the packaging with accessory that form no part of the claimed design.

1 Claim, 5 Drawing Sheets

Related U.S. Application Data

a continuation of application No. 29/706,554, filed on Sep. 20, 2019, now Pat. No. Des. 896,629, which is a continuation of application No. 29/670,716, filed on Nov. 19, 2018, now Pat. No. Des. 861,498, which is a continuation of application No. 29/632,039, filed on Jan. 4, 2018, now Pat. No. Des. 833,887, which is a continuation of application No. 29/575,695, filed on Aug. 26, 2016, now Pat. No. Des. 808,281.
